DESIGN FOR A PILLOW COVERING OR SIMILAR ARTICLE

Benjamin Norman, New York, N. Y.

Application November 14, 1939, Serial No. 88,276

Term of patent 3½ years

To all whom it may concern:

Be it known that I, Benjamin Norman, a citizen of the United States of America, residing in New York city, in the Borough of Manhattan, county and State of New York, have invented a new, original, and ornamental Design for a Pillow Covering or Similar Article, of which the following is a specification, reference being had to the accompanying drawing, forming part thereof, wherein the figure is a front view of a pillow covering showing my new design.

The rear of the pillow covering is substantially the same in appearance as the front.

I claim:

The ornamental design for a pillow covering or similar article, substantially as shown, and described.

BENJAMIN NORMAN.
